DAVID G. McCAA, OF LANCASTER, PENNSYLVANIA, ASSIGNOR OF ONE-HALF TO
CORNELIUS D. EHRET, OF MOUNT AIRY, PHILADELPHIA, PENNSYLVANIA.

TRANSMITTING APPARATUS.

1,382,206.

Specification of Letters Patent. Patented June 21, 1921.

Application filed January 19, 1920. Serial No. 352,465.

To all whom it may concern:

Be it known that I, DAVID G. McCAA, a citizen of the United States, residing in the city of Lancaster, county of Lancaster, State 5 of Pennsylvania, have invented a new and useful Transmitting Apparatus, of which the following is a specification.

My invention relates to apparatus for transmitting high frequency energy under 10 control of a microphone or other signaling instrument whereby no energy will be impressed upon the natural or artificial medium extending between transmitting and receiving stations until sound waves or 15 speech are uttered into the microphone, or until other control is effected.

For an illustration of one of the modes of practising my invention, reference is had to the accompanying drawing, which is a diagrammatic view of transmitting apparatus 20 embodying my invention and suitable for practising my method.

Referring to the drawing, V is a thermionic or electronic oscillator, or any equivalent or suitable source of high frequency oscillations such as used in radio or carrier wave systems, the frequency of the oscillations preferably being high, as, for example, well above audibility.

30 The coils L and L¹ couple the circuit of the anode a with the circuit of the grid g, the filament f being supplied by current from battery b and regulated by resistance r. In the plate or anode circuit is the battery B which may be shunted by the condenser C¹. There is associated also in the aforementioned circuits the primary P and the variable condenser C.

In inductive relation with the primary P 40 are the secondaries S and S¹ so wound or connected that at a given instant of time they exhibit at similar ends similar polarities. In shunt to the secondaries are preferably employed the variable tuning condensers C² and C³ for tuning the secondary circuits to the frequency of the oscillations in the primary P.

V¹ is a thermionic or electronic amplifier comprising two anodes a¹ and a² and two grids g¹ and g², coöperating with a common filament f, when all the electrodes are placed in one evacuated vessel, as indicated. It will be understood, however, that two separate amplifiers may be employed, each comprising filament, grid and anode.

One terminal of each of the secondaries S¹ and S² is connected by conductor 1 with the cathode or filament f of the amplifier V¹. The other terminal of the secondary S¹ connects through the secondary S³, which may be shunted by the variable condenser C⁴, and through the conductor 2 with the grid g¹. Similarly, the other terminal of the secondary S² connects through the secondary S⁴, which may be shunted by a variable condenser C⁵, and through conductor 3 with grid g². In the circuit of the anode a¹ is the primary P³ of an oscillation transformer, shunted by the tuning condenser C⁶ for tuning the anode circuit to the frequency of the oscillations produced by the oscillator V. Similarly, in the circuit of the anode a² is an oscillation transformer primary P⁴ whose circuit is tuned to like frequency by the variable condenser C⁷. The battery B¹ supplies the energy for the anode circuits, the potential or current strength in said plate circuits being adjustable by varying or adjusting the points on resistances r¹ and r², at which the anode circuits connect.

With the apparatus thus far described, with oscillations of suitable radio or carrier wave frequency existing in the primary P, there will be impressed upon the grids g¹ and g² similar and equal electro-motive-forces, whereby in the circuits of the anodes a¹ and a² there will be repeated oscillations of like radio or carrier wave frequency. Inductively related with the primaries P³ and P⁴ are the secondaries S⁵ and S⁶, connected in the antenna system comprising the antenna A, tuning inductance L² and earth connection E. When the apparatus is properly balanced, there will be no high frequency energy in the antenna circuit because of the opposed relations of the primaries P³, P⁴ and the secondaries S⁵ and S⁶.

Coupled with the secondaries S³ and S⁴ are the primaries P¹ and P², connected in circuit with the battery b¹ and microphone m. When the microphone is at rest, normally the current from the battery b¹ is not varied, and therefore there is no inductive effect by the primaries P¹ and P² upon their secondaries S³ and S⁴, and accordingly there is no high frequency energy in the antenna A.

If, however, sound waves or speech be uttered at the microphone, electro-motive-forces varying in accordance with speech

will be induced in the secondaries S^3 and S^4 , and these are so connected in circuit, or so related with their primaries P^1 and P^2 , that the electro-motive-force variations due to speech effect changes of potential in opposite senses on grids g^1 and g^2 . That is to say, while g^1 is increasing in potential, grid g^2 decreases in potential. The result is that the high frequency oscillations, repeated and amplified in the primaries P^3 and P^4 , are in one of them increased and in the other simultaneously decreased in amplitude. Accordingly, the inductive effect of the primaries P^3 and P^4 upon the secondaries S^5 and S^6 is no longer zero; the cumulative effect of the primaries upon the secondaries is such that there exists in the antenna system high frequency oscillations varying in amplitude in accordance with sound waves or speech.

Instantly the voice or sound waves cease at the microphone m , high frequency energy ceases in the antenna system; and similarly, instantly sound waves or speech is initiated and continued at the microphone m , oscillations are present in the antenna system and vary in accordance with speech.

What I claim is:

1. The combination with a source of oscillations of high frequency, a primary traversed thereby, secondaries similarly inductively affected by said primary, thermionic devices comprising grid and anode circuits, said grids similarly affected by said secondaries whereby the oscillations in the anode circuits are substantially equal, means in series with said secondaries controlled by sound waves for affecting said grids in opposite senses, a transmitting conductor, and a differential coupling between said conductor and said anode circuits, whereby only when sound waves are present high frequency energy appears in said conductor.

2. The combination with thermionic devices each comprising a cathode, grid and anode, of a source of current common to their anode circuits, resistances connected across the terminals of said source and connected in series, respectively, with the different anode circuits, an output circuit, and means in each anode circuit other than the resistance therein for affecting said output circuit.

3. The combination with a plurality of thermionic devices each comprising a cathode, grid and anode, an output circuit, a differential coupling between said circuit and the anode circuits, a transformer primary traversed by fluctuating current, secondaries inductively coupled to said primary and connected, respectively, in series with said grids and for affecting their potentials in like senses, transformer secondaries in series with said secondaries and said grids and affecting the potentials of said grids in

opposite senses, and signaling means coupled to said second named secondaries.

4. The combination with thermionic devices each comprising a cathode, grid and anode, of a source of current common to their anode circuits, resistances connected across the terminals of said source and connected in series, respectively, with the different anode circuits, an output circuit, and an inductive coupling between each anode circuit and said output circuit.

5. The combination with a plurality of thermionic devices each comprising a cathode, grid and anode, an output circuit, a differential coupling between said circuit and the anode circuits, a transformer primary traversed by fluctuating current, secondaries inductively coupled to said primary and connected, respectively, in series with said grids and affecting their potentials in like senses, transformer secondaries in series with said secondaries and said grids and affecting the potentials of said grids in opposite senses, and a telephone transmitter coupled to said second named secondaries.

6. The combination with a plurality of thermionic devices each comprising a cathode, grid and anode, of a source of current, resistances connected across said source connected in the respective anode circuits, an output circuit, and means in each anode circuit other than the resistance therein for affecting said output circuit.

7. The combination with a plurality of thermionic devices each comprising a cathode, grid and anode, of a source of current, resistances connected across said source connected in the respective anode circuits, means for varying the portions of said resistances included in said anode circuits, an output circuit, and means in each anode circuit other than the resistance therein for transferring energy to said output circuit.

8. The combination with a plurality of thermionic devices each comprising a cathode, grid and anode, said cathodes, grids and anodes disposed within the same evacuated chamber, of a source of current, and resistances connected across the terminals of said source externally of said chamber and connected in the respective anode circuits.

9. The combination with a plurality of thermionic devices each comprising a cathode, grid and anode, said cathodes, grids and anodes disposed within the same evacuated chamber, of a source of current, resistances connected across the terminals of said source externally of said chamber and connected in the respective anode circuits, and means for varying the relative magnitudes of said resistances.

In testimony whereof I have hereunto affixed my signature this 16 day of January, 1920.

DAVID G. McCAA.
